Primary Examiner — Cynthia Ramirez*Assistant Examiner* — Gino Colan*(74) Attorney, Agent, or Firm* — David M. Kleiman**CLAIM**

The ornamental design for an air vent device, as shown and described.

DESCRIPTIONFIG. 1 is a front, left side perspective of the air vent device.
FIG. 2 is a front view of the air vent device.

FIG. 3 is a back view of the air vent device.

FIG. 4 is a right side view of the air vent device.

FIG. 5 is a left side view of the air vent device.

FIG. 6 is a top view of the air vent device; and,

FIG. 7 is a bottom view of the air vent device.

The broken lines in the figures are to show portions of the air vent device and form no part of the claimed design.
